Attns.

UNITED STATES PATENT OFFICE

ALBERT H. DYKES, OF REVERE, MASSACHUSETTS, ASSIGNOR OF ONE-HALF TO CARROLL
B. DAY, OF BOSTON, MASSACHUSETTS

GUN LOCK

Application filed July 30, 1927. Serial No. 209,524.

My invention relates to firearms, and more particularly aims to provide an improved and simplified lock mechanism for plural-barrel guns, it being especially adapted for 5 use with double-barrel shot-guns.

In the drawings illustrating by way of example one embodiment of my invention,

Fig. 1 is a left side elevation of the gun frame and breech portion, partly in vertical 10 section and with the stock removed, both hammers being in cocked position;

Fig. 2 is a left side elevation, on a larger scale, of the trigger mechanism of Fig. 1, one barrel, the left as illustrated, having been 15 fired by the corresponding trigger which as shown is assumed still to be retained in "pulled" position by finger pressure upon it;

Fig. 3 is a view similar to Fig. 2 but with 20 the parts in the relative position occupied after the finger pressure has been released from the "pulled" trigger of Fig. 2 and the other barrel fired by pull on either trigger;

Fig. 4 is a detail plan view of a part hereinafter termed the blocking lever; and

Fig. 5 is a detail view in front elevation of a part to be termed herein the interceptor.

My invention is useful in connection with any plural-barrel gun but for the purpose of 30 illustration I have shown it in connection with a double-barrel shot-gun, which may be of any desired or usual construction and may be of the so called "hammer" or "hammer-less" type. In Fig. 1 I have shown, more or 35 less conventionally, sufficient of the usual gun parts as will be necessary to an understanding of my invention.

Referring more particularly to the drawings and first to said Fig. 1, the lock-casing or frame is indicated at 1, and the rear of the barrels at 2, the usual breech lever or barrel-locking lever being shown at 3. The hammers 4, 4 for the respective barrels are pivoted in the casing at 5. Each hammer is 45 provided with a bent or cocking notch 6 with which the forward end or nose 7 of the corresponding sear 8 engages to hold the hammer cocked.

Each hammer is so constructed and arranged that the distance from the hammer

pivot 5 to the bottom of the cocking notch 6 is less than the distance from said hammer pivot to the surface of the hammer portion 9 against which its sear nose rests in the down or fired position of the hammer. These proportionate distances may be provided either by forming a deeper cocking notch than is customary or by supplying extra material upon the hammer, forming a nub or projection at the portion 9 in the manner illustrated 55 in the drawings. By reason of the described hammer construction the rear end or tail 10 of each sear will occupy a higher position when its hammer is down or fired than when the latter is up or cocked; see Fig. 2. Aside 60 from the trigger mechanism proper this change in the hammer construction, which may be readily effected in either of the manners stated, is the only modification of any 65 standard gun part necessary in connection with my invention. In Fig. 1 the main spring or hammer spring, the cocking lever, the sear spring and other parts not necessary herein to illustrate have been omitted for the sake of clearness.

Upon the trigger plate 11, which may be of the usual form, is mounted the customary block or trigger box 12. The left and right hand trigger blades 13 and 14 respectively are pivoted at their forward ends in said trigger box in the usual manner, as at 15, the left trigger being provided with a finger piece 16 and the right trigger with the finger piece 17. Each trigger is formed with sear-step or sear-tail-engaging portion 18, in the 75 usual manner.

In accordance with my present invention the two triggers are inter-connected, and in a manner permitting either trigger first to move independently of the other and thereafter to move said other or said other may be moved by engagement of the finger directly with it. While any suitable connecting means between the triggers may be employed for this purpose, I have illustrated a pin 19 90 near the rear end of one trigger, herein the right trigger, projecting laterally and extending into a slot 20 in the adjacent portion of the other trigger, herein that at the left. Said pin and slot are so constructed and pro- 95 100

portioned that with both hammers cocked the pin stands about midway of the slot and during the first pull of either trigger the pin and slot have no operative engagement, but

5 the pin and one end wall of the slot become engaged at the end of said first pull so that upon subsequent pull of either trigger, when the other parts to be described permit, the unfired hammer will be released. It will be
10 understood that the slot may be formed in either trigger and the pin positioned upon the other, and I have shown the pin on the right trigger and the slot in the left merely for the purpose of illustration and description.
15

Associated with the triggers and their sears I provide an improved and simplified means for controlling the trigger action, whereby the trigger pulled in firing the first barrel 20 must be released before said trigger can be pulled to fire the other barrel, thus preventing the occurrence of "doubling." It will be understood that by reason of the described construction both barrels may be fired by 25 means of either trigger alone, or they may be fired each by its own trigger. By pulling first the left trigger the left barrel will be fired first, and then either a second pull on said left trigger or pull of the right trigger 30 will fire the right barrel. The reverse firing sequence occurs by use of the right trigger first. No special setting or switching of any part is required to permit the firing of either or both barrels and in either sequence.
35

Supported upon and projecting rearwardly from the trigger box 12 is a bracket 23 near the rear portion of which is pivotally supported as at 24 a member 25 which will hereinafter be termed the interceptor. Said 40 interceptor 25, seen in detail in front elevation in Fig. 5, includes a forwardly projecting arm 26 between which and the adjacent portion of the bracket 23 bears a suitable spring of any desired type, herein illustrated 45 as a coil spring 27. Said interceptor also includes a depending yoke-shaped portion the two legs 28, 28 of which each terminate in a nose 29 adapted at certain times respectively to be engaged in the interceptor notch 50 30 of the corresponding trigger blade, immediately forward of the sear-step 18. As illustrated, see Fig. 5, the two nose portions 29 are cross connected. The forward edge of the interceptor, that is, toward the left in 55 the drawings, is formed with a curved or cam portion 31 terminating downwardly in a boss or projection 32, one at the forward edge of each leg.

It will be noted, particularly from examination of Fig. 2, that the pivot 24 of the interceptor is so located with relation to the interceptor noses 29, 29 that movement of the latter forwardly or away from the interceptor notches 30, 30 of the trigger blades will 60 immediately be along an upward or rising

arc centered at said pivot point, the latter being preferably slightly to the rear of the interceptor noses when either of them is engaged in its notch 30.

Cooperating with said interceptor is a 70 blocking-lever 33 pivoted at its forward end in the trigger box 12, as at 34. Said blocking-lever, as seen in detail in Fig. 4, has a rear end of approximately T-shape, the opposite ends of the rear or cross-piece 35 lying respectively directly above the tails 10, 10 of the two sears 8, 8. Forwardly of said cross-piece 35 the blocking-lever is provided with a pair of opposed laterally projecting shoulders 36, 36 the rear faces of which, when 80 both hammers are cocked, lie directly in advance of and across the projections 32 of the interceptor, holding the latter rearwardly and against or adjacent the upper portion 85 of the rear walls of the interceptor notches, as shown in Fig. 1. At other times said shoulders may move along and in engagement with the cam portion 31 of the interceptor. The blocking-lever is urged downwardly by a suitable spring herein illustrated as a coil spring 37 intermediate said lever and the bracket 23 and designed to be somewhat stronger than the interceptor spring 27.
90

The operation of the lock mechanism of my invention will be understood from the foregoing description taken in connection with the drawings. Assume that it is desired to fire first the left barrel and then the right barrel, firing both by the use of one trigger, both hammers being cocked as shown in Fig. 1. A pull upon the finger piece 16 of the left trigger lifts its trigger blade 13, carrying upwardly with it the tail 10 of the left sear 8 and also lifting the blocking lever 33, since the rear end of the latter bears upon the sear. When the hammer has fallen to fire the left barrel, its sear-tail comes to rest in a raised position substantially as shown in Fig. 2. The blocks or 100 shoulders 36, 36 of the blocking-lever 33 have now been moved upwardly out of horizontal alignment with the projections 32 on the interceptor, but so long as the finger pressure is retained on the trigger the interceptor blocks further trigger movement, being held rearwardly by engagement of its nose 105 29 in the notch 30 of the left trigger blade. The interceptor in said position positively 110 blocks and prevents further upward movement of the left trigger prior to release of the latter.
115

As soon as but not until the finger pressure is removed from the left trigger the interceptor nose 29 moves forwardly out of the engaged notch in the trigger and into the position substantially as shown in Fig. 3. This movement of the interceptor is effected by its spring 27, taking place in an 120 upward arc about the interceptor pivot 24.
125

In said released position of the trigger said spring 27 is free to move the interceptor in the manner described since the blocking-lever 33 is out of engagement with the interceptor, the pressure of its stronger spring 35 being sustained by the raised sear-tail 10.

Either trigger may now be pulled to fire the right barrel. The first pull of the left trigger has brought the bottom of the slot 20 up into engagement with the pin 19 so that further pull of said left trigger will lift the right trigger by means of said pin. A pull of the right trigger will of course actuate that trigger and its sear directly. It will be understood that a similar operation takes place when the right trigger is pulled first, to fire first the right barrel, with the sole difference that the second pull of the right trigger operates on the other trigger by engagement of the pin 19 with the top of the slot 20 instead of the bottom as previously described.

When the gun is re-loaded or re-cocked the sears both resume their former position with tails down, as in Fig. 1. Upon such lowering of the sear-tails the blocking lever 33 returns to its position wherein its shoulders 36, 36 lie in line with the projections 32 on the interceptor, holding the latter back against the trigger. This return movement of the blocking lever is effected by its spring 37 which, being stronger than the interceptor spring 27, forces said shoulders 36, 36 down along the cam surface 31 at the forward edge of the interceptor, camming the latter rearwardly into position above the trigger notches 30.

It will be observed that the described trigger mechanism, which produces in effect a double single-trigger gun includes, excepting the pin 20, but three working parts and two small springs, namely the bracket 23, the interceptor 25 and the blocking-lever 31 all of which are supported upon the usual trigger box 12. Said parts are all so positioned and are so compactly arranged that no additional cutting away of the wood of the stock is necessary, whereby the gun is in no wise weakened at its throat, its weakest portion. Moreover the provision of the described mechanism does not interfere with any existing safety mechanism, such for example as a safety lever to engage the notches 38 at the rear of the trigger blades and not necessary to illustrate herein. The mechanism also can readily be adapted, as by the provision of a suitable slide, for use with a single-trigger plural-barrel gun to determine selectively the sequence of firing of the respective barrels.

In addition to the extreme simplicity of the mechanism and its marked efficiency in preventing "doubling" while permitting the firing of the barrels in any order, the mechanism is susceptible of extreme speed in operation. It will be noted that the release or backward movement of a trigger after firing the first barrel is equal to only about one-half

the depth of the interceptor notch 30, since the interceptor in moving forwardly into trigger releasing position lifts along the upward arc of a circle, as previously described, thus reducing the distance through which the trigger must return upon release of the finger pressure before it can again be pulled to fire the other barrel.

My invention is not limited to the specific embodiment herein shown and described, its scope being set forth in the following claims.

I claim—

1. In a lock mechanism for a double-barrelled shot-gun having a trigger plate, two triggers and a like number of sears and hammers, a substantially vertical slot in one trigger blade and a pin on the other trigger blade projecting into said slot at about mid-length thereof in the positions of the triggers prior to firing either barrel, a trigger box on the trigger plate wherein the trigger blades are pivoted, a rearwardly projecting bracket on said box, an interceptor pivoted on said bracket and lying above both trigger blades, a spring urging said interceptor forwardly, a blocking lever holding said interceptor rearwardly against the adjacent portions of the trigger blades in their position prior to firing either barrel, said lever having a rearward extension bearing against both sear-tails, an upwardly and forwardly inclined notch in each trigger blade immediately below said interceptor in said rear position thereof, whereby upon initial pull of either trigger the interceptor will engage in the notch thereof and prevent further pull of the trigger prior to release of the finger pressure thereon and will be retained in said notch during the continuance of said pressure, said interceptor spring acting to move the interceptor forwardly out of said notch to allow further pull of said trigger to fire the other barrel through said pin and slot connection when the finger pressure on the trigger is released, said forward movement being permitted by reason of the lifting of the blocking-lever out of said interceptor holding position by the raising of the tail of the sear of the barrel first fired.

2. In a lock mechanism for a double-barrelled shot-gun having a trigger plate, two triggers and a like number of sears and hammers, a substantially vertical slot in one trigger blade and a pin on the other trigger blade projecting into said slot at about mid-length thereof in the positions of the triggers prior to firing either barrel, a trigger box on the trigger plate wherein the trigger blades are pivoted, a rearwardly projecting bracket on said box, an interceptor pivoted on said bracket and lying above both trigger blades, a spring urging said interceptor forwardly, a blocking lever holding said interceptor rearwardly against the adjacent portions of the trigger blades in their position prior to

firing either barrel, said lever having a rearward extension bearing against both sear-tails, an upwardly and forwardly inclined notch in each trigger blade immediately below 5 said interceptor in said rear position thereof, said blocking lever being movable out of interceptor holding position by movement of the tail of the sear of the first barrel, and spring means tending to move said blocking 10 lever in the opposite direction to that in which it is moved by a sear-tail.

3. In a lock mechanism for a double-barrelled shot-gun having a trigger plate, two triggers and a like number of sears and hammers, a substantially vertical slot in one trigger blade and a pin on the other trigger blade projecting into said slot at about mid-length thereof in the positions of the triggers prior to firing either barrel, a trigger box on the 15 trigger plate wherein the trigger blades are pivoted, a rearwardly projecting bracket on said box, an interceptor pivoted on said bracket and lying above both trigger blades, a spring urging said interceptor forwardly, 20 a blocking lever holding said interceptor rearwardly against the adjacent portions of the trigger blades in their position prior to firing either barrel, said lever having a rearward extension bearing against both sear- 25 tails, an upwardly and forwardly inclined notch in each trigger blade immediately below said interceptor in said rear position thereof, whereby upon initial pull of either trigger the interceptor will engage in the 30 notch thereof and prevent further pull of the trigger prior to release of the finger pressure thereon and will be retained in said notch during the continuance of said pressure, said interceptor spring acting to move 35 the interceptor forwardly out of said notch to allow further pull of said trigger to fire the other barrel through said pin and slot connection when the finger pressure on the trigger is released, said forward movement 40 being permitted by reason of the lifting of the blocking-lever out of said interceptor holding position by the raising of the tail of the sear of the barrel first fired, and spring means to return said interceptor and block- 45 ing lever to their original positions upon recocking of the gun.

4. In a double-barrelled shot-gun, two triggers interconnected for movement either independently or one after and by the other, 55 an interceptor having a rear and a forward position, spring means urging it forwardly, said interceptor in its rear position adapted to interrupt movement of either trigger when it has fired its barrel, a blocking and position- 60 ing lever for said interceptor to position and hold it in readiness so to interrupt either trigger, and means whereby said lever releases said interceptor to permit it to assume 65 its forward position out of the trigger path

after interrupting a trigger and after finger pressure on the latter is removed.

5. In a double-barrelled shot-gun, two triggers interconnected for movement either independently or one after and by the other, 70 an interceptor having a rear and a forward position, spring means urging it forwardly, said interceptor in its rear position adapted to interrupt movement of either trigger when it has fired its barrel, a blocking and position- 75 ing lever for said interceptor to position and hold it in readiness so to interrupt either trigger, said lever having a portion engaging both sears whereby pull of either trigger will remove the lever from said interceptor-holding position, spring means urging said lever in the direction opposite that in which it is moved by the sear, a cam on the interceptor and a cooperating formation on said lever whereby, on recocking of the mechanism, said 80 spring means will return said lever and cause it to reposition and hold said interceptor.

6. Lock mechanism for a plural-barrelled gun comprising in combination with a sear and a hammer for each barrel, means on each hammer providing a depressed or cocked position for the sear-tail and a raised or fired position therefor, trigger means operable to release one or the plurality of sears successively and in one or the reverse order, an interceptor positioned to engage and restrain further movement of said trigger means upon release of one sear and during continuance of the finger pressure on said trigger means, a blocking lever engageable with said interceptor to hold it in position so to engage the trigger means and movable by the first released sear out of said interceptor-holding position, spring means to move said interceptor out of the path of the trigger means upon release of the finger pressure thereon, 90 spring means for said blocking lever, and cooperating formations on said lever and interceptor whereby return movement of said lever by its spring means upon re-cocking of the hammers and resulting depression of the sear-tails will return said interceptor to said position wherein it is held by said lever in readiness to engage and restrain the trigger means.

7. In a plural-barrelled firearm, trigger mechanism including a trigger for each barrel, trigger interconnecting means whereby single pull of one trigger will fire its barrel and either further pull of said trigger or pull of the adjacent trigger will fire the adjacent barrel, interceptor means to limit trigger movement on first pull to only that necessary to fire its barrel, and means to remove said interceptor means from trigger-movement limiting position upon release of the pulled trigger.

8. In a plural-barrelled firearm, trigger mechanism including a trigger for each barrel, trigger interconnecting means whereby single pull of one trigger will fire its barrel

and either further pull of said trigger or pull of the adjacent trigger will fire the adjacent barrel, movable means positioned to engage and prevent movement of a trigger beyond 5 that required to fire its barrel, means on the trigger retaining said movable means in said movement-preventing position while the trigger is still held by the finger, and spring means effective upon release of the trigger to 10 remove said movable means from the path of the latter.

9. In a plural-barrelled firearm, trigger mechanism including a trigger for each barrel, trigger interconnecting means whereby 15 single pull of one trigger will fire its barrel and either further pull of said trigger or pull of the adjacent trigger will fire the adjacent barrel, movable means positioned to engage and prevent movement of a trigger beyond 20 that required to fire its barrel, means on the trigger retaining said movable means in said movement preventing position while the trigger is still held by the finger, spring means effective upon release of the trigger to remove 25 said movable means from the path of the latter, and spring-actuated means to return said movable means to its first position upon re-cocking of the gun.

10. In a double-barrelled shot-gun, triggers 30 13 and 14 interconnected for movement either independently or one after and by the other, hammers 4, 4, sears 8, 8, said hammers constructed and arranged to afford a higher position for a sear-tail 10 when fired than 35 when cocked, a pivoted interceptor 25 having portions 29, 29 engageable in notches 30, 30 in the respective triggers, spring means 27 urging said interceptor forwardly from said notches, a blocking lever 33 having shoulders 40 36, 36 engageable with said interceptor to hold the latter rearwardly with said portions 29, 29 above but out of engagement with said notches in the unfired position of the triggers, said lever 33 having a cross-piece 35 45 engageable by both sear-tails, whereby either sear will lift the lever out of interceptor-holding position, spring means 37 urging said lever 33 in the direction opposite that in which the sear-tails lift, and a cam formation 31 on the interceptor engageable by said shoulders 36, 36 of the blocking lever to return the interceptor rearwardly when the mechanism is recocked.

11. In a double-barrelled shot-gun, in combination with the lock mechanism including, for each barrel, a hammer, a sear, and a trigger, cooperating formations on each sear and hammer whereby the sear-tail has a depressed or cocked position and a raised or fired position, each trigger operable upon the first portion of its full movement to release its sear to fire its barrel, inter-trigger connections whereby either subsequent full movement of the pulled trigger or movement of 60 65 the other trigger will release the other sear to

fire the other barrel, means to intercept the movement of either trigger upon completion of said first movement, and means to cause said means to free the pulled trigger for further and complete firing movement upon release of the finger-pressure thereon. 70

12. In a lock mechanism for a double-barrelled gun having two triggers and a like number of sears and hammers; a lateral projection on one trigger blade and an engageable formation on the other trigger blade; a trigger-box whereon the trigger blades are pivoted; an interceptor movably supported on said trigger-box and crossing both trigger blades; a spring co-operating with said interceptor; a blocking lever causing engagement of said interceptor with the trigger blades in their position prior to firing either barrel, said lever having a portion engaging both sear-tails; and a notch in each trigger blade adjacent said interceptor, whereby upon initial pull of either trigger the interceptor will engage in the notch thereof and prevent further pull of the trigger prior to release of the finger pressure thereon, said interceptor spring acting to move the interceptor out of said notch to allow further pull of said trigger to fire the other barrel when the finger pressure on the trigger is released. 80 85 90

In testimony whereof, I have signed my name to this specification. 95
